UNITED STATES PATENT OFFICE.

CHARLES E. PHILLIPS, THOMAS G. HODGES, AND RALPH D. ANDERSON, OF PRATT,
KANSAS.

FILM HOLDER.

Application filed November 9, 1925. Serial No. 67,789.

Our invention relates in general to holders for sheet materials and more particularly to devices adapted for holding sheets of thin material while they may be immersed in treating liquids or solutions, or exposed to the air for drying, or while subjected to other treatments.

In its more specific embodiment, it is an object of our invention to provide a device 10 adapted to hold cut photographic films, such as those formed of a pyroxylin composition or other suitable transparent material while these are immersed in or otherwise treated with developing, fixing or washing liquids, 15 exposed to the air for drying or subjected to other treatments.

The objects of our invention and its mode of operation will be more fully apparent 20 from the following description of a preferred form or embodiment of the invention taken together with the drawings illustrative of same, in which:—

Figure 1 is a side view of the device shown as carrying a film secured therein, the device and film being suspended in a tank 25 shown in cross section;

Figure 2 is a plan view of a preferred form of film holding clip looking downwardly and showing a film and a supporting rod on which the clip is mounted in cross section, along the line 2—2 of Figure 1;

Figure 3 is a plan view of the preferred form of clip or holder and a tension spring 30 adapted for holding the upper edge of a film, a supporting rod for the same being shown in cross section along the line 3—3 of Figure 1;

Figure 4 is a vertical, sectional view along the line 4—4 of the device as shown in Figure 1; and

Figures 5, 6 and 7 are detail views upon a larger scale, showing more clearly certain features of specific construction of our preferred device.

In its preferred embodiment, as shown in the drawings, our device, particularly adapted for use as a photographic film holder, may comprise a frame 1, which may be formed from a single piece of metal wire 45 or rod, or from other suitable material, and which will usually be of rectangular configuration and may be provided at its upper end with two outstanding or offset portions 2 and 3, adapted to rest upon the 50 upper edge of a developing tank or other

receptacle, in which the device and the film carried thereby may be suspended. It will be noted that the off-set 2 is longer than the off-set 3 where the two end portions of the single wire forming the frame 1 lie parallel, 60 the length being sufficient to form a handle for manipulating the frame in the developing or other tank and in addition operates to support the frame at one edge of the tank similarly to the off-set 3. Fixed at the lower 65 end of this frame 1 a clip 4 is provided, adapted for holding the lower edge of a cut film or other sheet material to be carried by the holder.

As more clearly shown in Figures 5 and 6, this clip in its preferred embodiment may comprise a member 5, which may be formed of a strip of sheet metal provided at its ends with rings or retaining devices 6, adapted to engage the upright members of the frame 75 1 and to hold the clip in position therebetween. The member 5 may also be provided with retaining rings or members 7, adapted similarly to engage the lower bar of the frame 1, thus holding the clip 4 in position 80 at the bottom of the frame. At suitable intervals, along the face of the member 5, retaining points 8 are positioned, these being formed preferably by stamping out or displacing suitably small triangular portions of the material of the member 5 itself, these 85 points being of any suitable number and spacing; for example, equally spaced and five in number, as shown in Figure 1, which has in practice been found to be a very satisfactory 90 construction, in the case of a holder for film 8 by 10 inches in size.

The upper edge portion of the member 5 may be bent into a horizontal position oppositely to the direction in which the points 95 8 extend, thus forming a stiffening flange 9 as shown in Figure 6. From the bottom of the member 5 integral lugs or extensions 10 may be provided, adapted to serve as stops for the bottom of a film or sheet of material when inserted in the clip 4. Adjacent the ends of the member 5 extensions 11 are formed, provided with openings 12, serving for the pivotal mounting of a cooperating member 13, which as shown in Figure 5 may be formed of a single piece of sheet metal 100 or other suitable material and may be provided, at its ends, with extensions 14, which are inserted in the openings 12 and serve as pivots upon which the member 13 may be 105 110

partially rotated conveniently by grasping the extension 15 provided thereon.

Secured to the frame 1 an upper clip 16 is provided, which, as shown in Figures 5 1, 3 and 7, may comprise a vertical member 17, preferably formed of sheet metal, provided on one side with points 18 (which may be formed similarly to the points 8 and which extend in the same direction) 10 and provided at its lower edge with an oppositely extending flange 19, serving in the same manner as the flange 9 as a stiffening and strengthening member. The member 17 is provided, at its ends, with guideways 15 20 loosely engaging the upper portions of the frame 1, whereby the clip 16, of which the member 17 constitutes a portion, is free to move within certain limits along the frame. At each end of the clip 16, tension 20 devices, such as springs 21, are provided one end being secured to an end of clip 16 and the other to the frame above the clip, whereby these tension devices tend to draw the clip upwardly when depressed below 25 its normal position. The clip 16 also comprises an eccentric retaining member, similar to or identical with the member 13 of the lower clip 4, and which may be similarly mounted and provided with a similar 30 extension 23 for convenience in manipulating the same. The upper clip is preferably also provided with suitable finger holes 22 for convenience in depressing the clip 16 in inserting a film or other piece of sheet 35 material in the device and removing the film or other sheet from the device.

Ordinarily and preferably, our holder will be formed of dimensions such that the distance between the upper and lower clips, 40 when the upper clip is in its normal position, corresponds to one dimension of a rectangular film or sheet, which the device is especially adapted to hold. In using the device, the eccentric retaining member 13 45 of the lower clip and the similar retaining member of the upper clip will be turned into such position that the jaws of the clips are open. The lower edge of the film or sheet will then be placed upon the extensions or stops 10 of the lower clip, the retaining member or eccentric 13 then being closed against the film or sheet, so that the points 8 engage the film and cooperate to retain it in place. The upper clip will then 50 be preferably slightly depressed from its normal position and while so depressed the upper edge of the film or sheet will be secured in the upper clip upon the points 18 in the same manner as the lower edge is 55 secured in the clip 4. The upper clip then being released from the operator's grasp is drawn upwardly again to its normal position by the tension members or springs 21, so that the film or sheet is held in a taut 60 and flat position in the holder which, to-

gether with the film, may be inserted in a tank of developing solution, or subjected to other treatments.

As is clearly shown in Figures 4 and 5, the portions of the clips provided with extension pivots 14 are rotatable through approximately a half revolution about their extension pivots 14 and are formed each with a flange or bearing surface which in closed position of the clip bears tightly 75 against the surface of the film adjacent one of its edges and clamps it tightly against the cooperating back plate of the clip, thus uniformly distributing whatever strain or tension the film may undergo along the entire edge of the film and minimizing the chance of tearing the film such as exists when the corners or other points of the film are locally subjected to undue and unequal stresses in other forms of holders of dissimilar construction.

Our device has been found especially suitable for holding films, such as used by physicians in X-ray photography during the development and subsequent fixing, washing and drying of such films. By the special construction of the device, as shown and described, the film is held at closely spaced intervals along the entire extent of two opposite edges and the tension and stress upon the film is approximately equally distributed over its different portions, thus minimizing or avoiding any chance of undue strain or tearing of the corners or other particular portions of the film.

Having described our invention, what we claim as new and desire to protect by Letters Patent is:—

1. A film support comprising a rectangular frame formed of a single piece of substantially rigid wire, and having two outstanding off-sets at its upper end adapted to engage the upper edge of a developing tank for suspending the frame therein, clips mounted on the frame adapted to engage a film uniformly along two parallel edges, one of said clips being movable to and from the other, and resilient means connecting the ends of the movable clip to opposite side members of the frame, whereby a film held between the two clips may be maintained taut under a substantially uniform tension.

2. A film support comprising a rectangular frame formed of a single piece of substantially rigid wire and having two outstanding off-sets at its upper end adapted to engage the upper edge of a developing tank for suspending the frame therein, a clip fixed to the lower end of the frame adapted to secure one edge of a film thereto, a clip for the other end of a film slidably mounted on two opposite side members of the frame in parallel relation to the fixed clip, U-shaped springs having their ends respectively fixed to said side members and to the ends of the

slidable clip, and finger loops formed in the latter constituting means for moving the slidable clip against the action of the springs.

3. A holder for cut photographic films comprising a rigid wire frame having a film clip secured thereto at a horizontal side thereof and a second film clip parallel to the first clip and slidable on the two vertical sides of the frame and springs between the frame and latter clip to retract it from the opposed clip to hold a film taut.

4. A holder for cut photographic films

comprising a rectangular frame having offsets at each side at the top one of which is elongated to form a handle, a film clip secured to the bottom of the frame and a second film clip parallel to the first clip and slidable on the sides of the frame and springs between the frame and said second clip. 15
